[57] CLAIM

The ornamental design for an easel or similar article.

DESCRIPTION

FIG. 1 is a perspective view of the article support taken from a point forwardly of and upwardly to the left of the forwardly facing front inclined panels of each support.

FIG. 2 is a perspective view of the article support of FIG. 1 taken from a point rearwardly of and downwardly to the left below the article support as illustrated in FIG. 1 revealing the upstanding central rear panel and associated gussets merging with the forwardly facing front inclined panels.

FIG. 3 is a side elevational view of the article support of FIG. 1 taken from the left side of same as viewed in FIG. 1 illustrating the left gusset section supporting the left front inclined panel.

The side elevational view of the article support of FIG. 1 taken from a point to the right of such support as viewed in FIG. 1 has not been shown in that it is a mirror image of the side elevational view of FIG. 3.

FIG. 1

FIG. 2

FIG. 3
